SOFT-SIDED HAND LUGGAGE HAVING
SHAPE-RETAINING END WALLSBenjamin Platt, Phoenix, Ariz., assignor to Platt
Luggage, Inc., Chicago, Ill., a corporation of
Illinois

Application June 19, 1947, Serial No. 755,688

8 Claims. (Cl. 190—53)

1

The present invention relates to hand luggage of the type having a pair of complementary sections of substantially rectangular shape and defining adjacent open sided compartments for the storage or transportation of articles, and particularly to hand luggage often termed or known as "soft" luggage. The present application is a continuation-in-part of my abandoned application Serial No. 543,987, filed July 8, 1944.

An object of this invention is to provide hand luggage of this type embodying improved stiffening or reinforcing means adapted to resist deformation or destruction of the bag and to thereby prolong its useful life. More particularly, the reinforcing means comprises end shells, which may be completely or partly preformed, forming portions of the end walls and having marginal flanges along three sides thereof for engagement with the side, top and bottom walls of their respective compartments. The shells are preferably secured to the walls adjacent thereto by means of stitching, although other forms of fastening means well known in this art may be employed, if desired.

This invention further contemplates improvements in design and construction of hand luggage whereby the cost of manufacture may be materially reduced and without detracting from the appearance or durability of the luggage.

This invention embodies other novel features, details of construction, and arrangement of parts which are hereinafter set forth in the specification and claims and illustrated in the accompanying drawings, wherein:

Fig. 1 is a fragmentary perspective view of a bag embodying the principles of this invention shown in its open position; the inner lining usually used in luggage of the type to which this invention pertains has been omitted from this and the other figures better to illustrate the invention;

Fig. 2 is an enlarged fragmentary sectional view taken along the line 2—2 of Fig. 1;

Fig. 3 is a detailed perspective view showing a preformed reinforcing shell employed in constructing the bag;

Fig. 4 is an enlarged fragmentary perspective view of an upper end portion of the bag, the bag being shown partly open;

Fig. 5 is an enlarged fragmentary perspective view of a lower end portion of the bag, the bag being shown partly open; and

Fig. 6 is a view similar to Fig. 3 of a modified reinforcing shell, the view showing the shell

2

covered by an associated covering, which may be leather.

Referring now to the drawings for a better understanding of this invention, and first to Figs. 1 to 5, inclusive, the bag illustrated may be seen to comprise two substantially identical sections or halves 8 and 9 which are generally rectangular in shape. Each includes a side wall 10, end walls 11, a top wall 12, and a bottom wall 13. The end and top walls are joined to the usual U-shaped jaws 16, which are hingedly connected at their ends by hinge structures 17, which may be of conventional construction.

In accordance with the primary feature of the present invention, certain of the end walls, preferably all, are provided with reinforcing shells 23, each of which is formed with a flange 24 extending along three sides thereof. The reinforcing shells give the bag considerable strength and rigidity, even though they are made of light material. They reinforce not only the end walls but, together with the flange portions 25, 26 and 27, add to the rigidity of the side, bottom and top walls, with the result that the ends of the bag, where damage would otherwise most readily occur, are reinforced against damage from all directions. Furthermore, the end shells enable the bag to be constructed more readily and economically.

The shells 23 may be completely preformed, as by stamping, of relatively thin, soft sheet metal but may be formed of wood, plastic, laminated fiber, or other material. Each shell is provided with a leather covering 28 secured, as by glue, to its outer side and disposed thereon and dimensioned to provide a lip 29 (see Fig. 2) extending along its unflanged edge whereby it may be secured, as by stitching, to a frame jaw. Each frame jaw is provided with a leather covering 31 which is glued thereto and has its edges 32 disposed inwardly, for stitching to the several walls, also as best illustrated in Fig. 2.

The bottom walls 13 include rectangular strips of cloth covered board 33 having an outer leather covering 34 secured thereto. A narrow strip of board 35 is located centrally of boards 33 to provide spacing for the hinges and to enable the bottom walls readily to move relative to each other when the bag is opened.

The side walls 10 comprise a layer of cardboard 36 or like material having an outer leather covering 37 secured thereto, these being extended to define also the top walls 12. The wall defining portions extend over considerable portions of the width of flanges 24 and over substantially the

entire lengths of flange portions 28 and 27 and over a short length of flange portion 26. The various wall defining portions and jaws may be readily stitched together to construct a complete bag.

The lips 29 of the end wall coverings 28 and the upper ends of the side and top wall defining portions 36 and 37 are secured to the inwardly facing side edges 32 of the frame jaw covering 31 by a row of stitches 38.

The lower ends of the portions 36 and 37 are secured to the bottom by stitching 39. The sides of the side and top wall defining portions 36 and 37 are secured to the end closure sections 11 by two rows of stitches 41 and 42 extending through the flanges 24 of the end shells 23. The rows of stitches 41 and 42 also extend across the top and bottom walls 12 and 13 to secure the latter to the end flanges 26 and 27 of the reinforcing shells 23. It may be noted that the bottom walls are secured to the inner sides of flange portions 26 whereas the side and top walls 11 and 12 are secured to the outer sides of the remaining flange portions. This minimizes the tendency of the stitching to be pulled out when the bag is heavily loaded and being carried in the usual manner.

Additional strength is given to the bag by the button headed bag supporting staples 43 having pointed ends adapted to pierce and be bent over against the inner side of the end flanges 26.

After the bag has been constructed in the illustrated and described manner, it is provided with the usual cloth inner lining, which has been omitted from the drawings more clearly to illustrate the construction of the bag. Suitable handles and latches may also be secured upon the jaw frames in the usual manner.

A modified form of end shell construction having certain advantages in facilitating construction of the luggage is illustrated in Fig. 6. The end shell is indicated as a whole by reference character 50 and it is preferably covered with leather 51 extending beyond the unflanged end of the shell as indicated by reference character 52.

To facilitate manufacture of the luggage, the shell 50 is only partly preformed. Thus, it is preformed with a top flange 53 and a side flange 54, which correspond to the flanges 27 and 25 of the shell 23. The shell is, however, provided with an extension 55 which can be bent during assembly of the luggage to provide a bottom flange corresponding to flange 26. The extension may be covered with leather, as shown, although in certain types of constructions it need not be. The leather can be glued to the shell and it can also be stitched to the flanges, as shown by stitching 56.

The use of an extension which can be bent during construction of the luggage is particularly advantageous because it enables the builder to locate the flange at the exact desired location of the bottom of the luggage. This is desirable in constructions employing jaw frames, like the frames 16, because the leather secured thereto does not always extend to the same place. As a result, the end wall may at times have to be somewhat shorter or longer, and with the described construction, its length can be controlled by bending the extension at the desired point.

The bending of the extension is facilitated and the appearance of the resulting structure enhanced by cutting the end of the extension 55 adjacent flange 54 on a bias, as indicated by reference character 56. This construction eliminates "interference" between the flanges.

It has been found that the support provided by the end shell having a separate flange 55 at the bottom is eminently satisfactory even though it is not integral with the side flange. However, it is not desirable to have such a flange at the top of the luggage.

From the foregoing description of the invention, it may be noted that one of the most important features thereof resides in the utilization of 10 either completely or partly preformed end shells having flanges extending around three sides thereof adapted to be stitched to the top, side and bottom walls of the bag. This construction facilitates the manufacture of hand luggage and 15 further provides sufficient strength to prevent collapse or deformation of the bag under practically all but the most unusual conditions.

While this invention has been shown in connection with the details of certain structures, it is 20 obvious to those skilled in the art that it is not so limited, but is susceptible of various changes and modifications without departing from the scope of the appended claims. For instance, the end shells may be made of different materials and 25 need not take the exact shape heretofore illustrated and described, and they may be used in bags other than those having substantially identical sections.

What I claim as new and desire to secure by 30 United States Letters Patent is:

1. In soft-sided hand luggage, a compartment-defining structure comprising top, side and bottom walls, and a pair of end structures secured respectively at opposite ends of the compartment, 35 each of said end structures including reinforcing means formed from a single blank and having a flat oblong end portion with dimensions corresponding substantially to the end of the compartment and having other portions extending inwardly from a top edge and one side edge of the end portion toward the other end structure, and a flexible sheet material covering on said reinforcing means; flexible sheet material forming at least parts of the top and side walls 40 of the compartment; and a flexible sheet material covered jaw frame secured to said end structures and top wall, said other inwardly extending portions of each of said reinforcing means being integral with each other to form a continuous inwardly extending structure whereby 45 said end structures define and maintain the outlines of the compartment.

2. In hand luggage as claimed in claim 1, 50 wherein each of said reinforcing means has associated with it a third other portion extending inwardly toward the other end structure from a bottom edge of said end portion.

3. In soft-sided hand luggage, a compartment-defining structure comprising top, side and bottom walls, and a pair of end structures secured respectively at opposite ends of the compartment, 60 each of said end structures including preformed single piece unitary substantially rigid reinforcing means having a flat oblong end portion with dimensions corresponding substantially to the end of the compartment and having flanges extending toward the other end structure from a top edge and one side edge of the end portion and forming a substantially continuous shape-retaining flange, and a flexible sheet material covering on said end portion and flanges; a flexible sheet material covered jaw frame secured to a side edge opposite the flanged side edge of said end structures and to said top wall; and flexible sheet material forming at least parts of the top 65

and side walls of the compartment, said material overlapping said flanges and being secured to said flanges, whereby said end structures define and maintain the outlines of the compartment.

4. In hand luggage as claimed in claim 3, wherein each of said reinforcing means includes a flange extending from a bottom edge of said end portion toward the other end structure.

5. In hand luggage as claimed in claim 3, wherein the flanges at the top and side edges of each of said reinforcing means are united and each reinforcing means includes a flange extending from a bottom edge of said end portion toward the other end structure, said flange at the bottom being united with the flange extending from the side edge of said end portion and covered with said sheet material covering.

6. In hand luggage as claimed in claim 3, wherein each of said reinforcing means includes a flange extending from a bottom edge of said end portion toward the other end structure, said flange being separate from the flange extending from the side edge of said end portion.

7. In hand luggage as claimed in claim 3, wherein junctures of the flanges with their associated end portion are smoothly rounded and wherein the flanges are rounded where the top and side flanges meet.

8. In hand luggage as claimed in claim 3, wherein the flexible sheet material covering on the end portion of each reinforcing means extends beyond said opposite side edge, the jaw frame covering sheet material extends beyond the frame, and the extending portions of the coverings are secured together.

BENJAMIN PLATT.
